UNITED STATES PATENT OFFICE.

WILLIAM JACOB WAMBAUGH, OF MORGANTOWN, WEST VIRGINIA.

LAMP-CHIMNEY.

1,122,049.

Specification of Letters Patent.

Patented Dec. 22, 1914.

Application filed May 27, 1914. Serial No. 841,214.

To all whom it may concern:

Be it known that I, WILLIAM J. WAMBAUGH, a citizen of the United States, and a resident of Morgantown, in the county of 5 Monongalia and State of West Virginia, have invented a new and Improved Lamp-Chimney, of which the following is a full, clear, and exact description.

The object of the invention is to provide 10 a new and improved lamp chimney adapted to be securely held in position on the chimney support of the lamp by the usual spring clamps to prevent the chimney from toppling over when carrying the lamp about 15 and to insure accurate centering of the chimney relative to the burner. In order to accomplish the desired result the base of the chimney is provided with a bearing surface in the form of a frustum of a cone 20 thus providing straight upwardly and inwardly inclined sides adapted to be engaged by the spring clamps of the chimney support to securely hold the chimney in position on the support at the same time allowing 25 expansion and contraction of the base without danger of being cracked by the spring clamps of the chimney support.

A practical embodiment of the invention is represented in the accompanying drawings 30 forming a part of this specification, in which similar characters of reference indicate corresponding parts in both views.

Figure 1 is a side elevation of the lamp chimney in position on a chimney support 35 shown in dotted lines, part of the chimney being shown in section; and Fig. 2 is an inverted plan view of the chimney.

The body A of the chimney is of usual shape while its base B is provided with a 40 bearing surface in the form of a frustum of a cone, the lower end of which terminates in an inwardly and downwardly inclined bottom portion C, the lower edge of which is adapted to be seated on the chimney support D provided with the usual spring clamps E adapt- 45 ed to bear against the outer face of the bearing surface of the base B. It will be noticed that by providing the base B with a bearing surface in the form of a frustum of

a cone, straight side edges are provided for 50 engagement throughout their height by the correspondingly shaped spring clamps E of the chimney support D, thus insuring an exceedingly strong hold of the clamps E on the said bearing surface to prevent the chimney 55 from toppling over when carrying the lamp about. It will also be noticed that by the arrangement described the chimney A is held in proper centering position relative to the burner and is not liable to shift laterally. 60 By bending the bottom C inwardly the curved portions of the spring clamps E are left unobstructed to allow the chimney clamps E to readily yield when placing the chimney in position on the support D or 65 when removing it therefrom. By the arrangement described a large contact is had between each spring clamp E and the bearing surface of the base B so that the said spring clamps E do not need to bear with 70 considerable force on the base of the chimney to hold the latter in place and consequently the base B can readily expand and contract without undue pressure on the part 75 of the chimney.

It is expressly understood that the use of a straight side edge of the base B instead of a curved edge is for the purpose of having it conform to that form of spring clamp that, while readily yielding for the insertion of the chimney base, will yet exert the greatest possible resistance to a force tending to withdraw said base from its hold. 80

Having thus described my invention, I claim as new and desire to secure by Letters 85 Patent:

1. A lamp chimney provided with a base having a circular bearing surface in the form of a frustum of a cone, thereby providing straight bearing sides inclined inwardly and upwardly and adapted to be engaged by the spring clamps of a chimney support. 90

2. A lamp chimney provided with a base having a circular bearing surface in the 95 form of a frustum of a cone thereby providing straight bearing sides inclined inwardly and upwardly and adapted to be en-

gaged by the spring clamps of a chimney support, the bottom portion of the base being bent directly from said straight sides inward and downward from the lower end **5** of the said bearing surface to allow the spring clamps to flex.

In testimony whereof I have signed my

name to this specification in the presence of two subscribing witnesses.

WILLIAM JACOB WAMBAUGH.
